(57) **CLAIM**

The ornamental design for an adjustable paper and cable retainer, as shown and described.

DESCRIPTION

FIG. 1 is a top perspective view for an adjustable paper and cable retainer showing my new design;

FIG. 2 is an enlarged perspective detail view of the head portion thereof;

FIG. 3 is an enlarged perspective detail view of the tail portion thereof;

FIG. 4 is a right detail view of the head portion where the left detail view is a mirror image thereof;
FIG. 5 is a front detail view of the head portion where the back detail view is a mirror image thereof;
FIG. 6 is a top thereof;
FIG. 7 is a right detail view of the tail portion thereof;
FIG. 8 is a front detail view of the tail portion where the back detail view is a mirror image thereof;
FIG. 9 is a bottom thereof;
FIG. 10 is a right side of a first embodiment thereof;
FIG. 11 is a front side of a first embodiment thereof;
FIG. 12 is a left side of a first embodiment thereof;
FIG. 13 is a back side of a first embodiment thereof;
FIG. 14 is a right side of a second embodiment thereof;
FIG. 15 is a front side of a second embodiment thereof;
FIG. 16 is a left side of a second embodiment thereof;
FIG. 17 is a back side of a second embodiment thereof;
FIG. 18 is a right side of a third embodiment thereof;
FIG. 19 is a front side of a third embodiment thereof;
FIG. 20 is a left side of a third embodiment thereof;

FIG. 21 is a back side of a third embodiment thereof;
FIG. 22 is a right side of a fourth embodiment thereof;
FIG. 23 is a front side of a fourth embodiment thereof;
FIG. 24 is a left side of a fourth embodiment thereof;
FIG. 25 is a back side of a fourth embodiment thereof;
FIG. 26 is a right side of a fifth embodiment thereof;
FIG. 27 is a front side of a fifth embodiment thereof;
FIG. 28 is a left side of a fifth embodiment thereof;
FIG. 29 is a back side of a fifth embodiment thereof;
FIG. 30 is a right side of a sixth embodiment thereof;
FIG. 31 is a front side of a sixth embodiment thereof;
FIG. 32 is a left side of a sixth embodiment thereof; and,
FIG. 33 is a back side of a sixth embodiment thereof.

FIGS. 1 through 9 are perspective and detail views for all embodiments. The break lines in FIGS. 2 through 5 and FIGS. 7 and 8 represent the boundary of the details shown in broken line in FIG. 1. The broken lines form no part of the claimed design.
